(57) **CLAIM**

The ornamental design for a vehicle bumper with internal storage and external mounting points, as shown and described.

DESCRIPTION

FIG. 1 is a top, right side perspective view, of a vehicle bumper with internal storage and external mounting points showing my new design, wherein the end is sealed.

FIG. 2 is a top, left perspective view thereof;

FIG. 3 is a top, right side perspective view, wherein the end is unsealed;

FIG. 4 is a top, left side perspective view thereof;

FIG. 5 is a bottom, right side perspective view thereof;

FIG. 6 is an enlarged end view thereof; and,

FIG. 7 is a top, right side perspective view showing my new design mounted on a travel trailer.

1 Claim, 3 Drawing Sheets

FIG. 1

FIG. 2
